Figure 3: A side cross-sectional view of a mechanical assembly. It features a main body 11 with a ribbed cylindrical section 11'. A central vertical rod 16 is connected to a base 18. A horizontal plate 9 is attached to the top of the rod 16. A coil spring 12 is wound around the rod 16. A rectangular block 10 is positioned between the spring 12 and the plate 9. A small circular component 14 is located on the left side of the block 10. A slot 15 is cut into the side of the block 10. A small circular component 13 is positioned above the slot 15. A horizontal rod 19 is attached to the left side of the block 10. A small circular component 8 is positioned below the slot 15. A small circular component 17 is positioned to the left of the slot 15. A small circular component 19' is positioned to the left of the slot 15. A small circular component 14' is positioned to the left of the slot 15. A small circular component 10' is positioned to the left of the slot 15. A small circular component 15' is positioned to the left of the slot 15. A small circular component 16' is positioned to the left of the slot 15. A small circular component 18' is positioned to the left of the slot 15. A small circular component 6' is positioned to the left of the slot 15. A small circular component 11' is positioned to the left of the slot 15.

Figure 4: A side cross-sectional view of a mechanical assembly. It features a main body 19 with a ribbed cylindrical section 19'. A horizontal plate 21 is attached to the top of the body 19. A central vertical rod 22 is connected to the plate 21. A coil spring 23 is wound around the rod 22. A rectangular block 24 is positioned between the spring 23 and the plate 21. A slot 25 is cut into the side of the block 24. A small circular component 26 is positioned above the slot 25. A small circular component 27 is positioned to the left of the slot 25. A small circular component 28 is positioned to the left of the slot 25. A small circular component 29 is positioned to the left of the slot 25. A small circular component 30 is positioned to the left of the slot 25. A small circular component 31 is positioned to the left of the slot 25. A small circular component 32 is positioned to the left of the slot 25. A small circular component 33 is positioned to the left of the slot 25. A small circular component 34 is positioned to the left of the slot 25.

Figure 5: A side cross-sectional view of a mechanical assembly. It features a main body 19 with a ribbed cylindrical section 19'. A horizontal plate 21 is attached to the top of the body 19. A central vertical rod 22 is connected to the plate 21. A coil spring 23 is wound around the rod 22. A rectangular block 24 is positioned between the spring 23 and the plate 21. A slot 25 is cut into the side of the block 24. A small circular component 26 is positioned above the slot 25. A small circular component 27 is positioned to the left of the slot 25. A small circular component 28 is positioned to the left of the slot 25. A small circular component 29 is positioned to the left of the slot 25. A small circular component 30 is positioned to the left of the slot 25. A small circular component 31 is positioned to the left of the slot 25. A small circular component 32 is positioned to the left of the slot 25. A small circular component 33 is positioned to the left of the slot 25. A small circular component 34 is positioned to the left of the slot 25.

Figure 6: A circular view of a cross-section of a component. It shows a rectangular block 24 with a slot 25. A small circular component 22 is positioned above the slot 25. A small circular component 21 is positioned to the right of the slot 25. A small circular component 19 is positioned to the right of the slot 25. A small circular component 23 is positioned to the left of the slot 25.

Figure 7: A circular view of a cross-section of a component. It shows a rectangular block 24 with a slot 25. A small circular component 22 is positioned above the slot 25. A small circular component 21 is positioned to the right of the slot 25. A small circular component 19 is positioned to the right of the slot 25. A small circular component 23 is positioned to the left of the slot 25.

Figure 8: A circular view of a cross-section of a component. It shows a rectangular block 24 with a slot 25. A small circular component 22 is positioned above the slot 25. A small circular component 21 is positioned to the right of the slot 25. A small circular component 19 is positioned to the right of the slot 25. A small circular component 23 is positioned to the left of the slot 25.

UNITED STATES PATENT OFFICE

BERTRAM J. GOLDSMITH, OF NEW YORK, AND AMBROSIUS BRIECHLE, OF BROOKLYN, NEW YORK, ASSIGNEES, BY MESNE ASSIGNMENTS, TO THE ENGLISH & MERSICK COMPANY, OF NEW HAVEN, CONNECTICUT, A CORPORATION OF CONNECTICUT

DOOR-LATCH CONSTRUCTION

Application filed November 12, 1925. Serial No. 68,490.

This invention relates to latchbolts for doors and more particularly to latchbolts for automobile doors.

The principle object of the invention is the production of novel mechanism permitting the latchbolt to be latched or dogged against movement by actuation of a handle on the outside of the door which latching means, however, is automatically released from latching position when a handle on the inside of the door is actuated to actuate the latchbolt.

A further object of the invention is the production of a mechanism permitting the inside handle to be located remote from the latch bolt and in a position permitting it to be easily accessible.

Still a further object of the invention is the production of the latchbolt mechanism having rotatable actuating means for retracting said latchbolt upon rotation thereof in either direction.

Further objects and advantages of the invention will appear from the accompanying description.

In the annexed drawings showing a practical embodiment of the invention:

Fig. 1 is a side elevation of a door (partly broken away) showing the invention applied thereto.

Fig. 2 is a horizontal section on the line 2—2 of Fig. 1.

Fig. 3 is an enlarged horizontal section on the line 3—3 of Fig. 1.

Fig. 4 is a horizontal section on the line 4—4 of Fig. 1 showing some of the parts in one position.

Fig. 5 is a similar view showing the parts in a different position.

Fig. 6 is a side elevation of a portion of the device with the parts in one position.

Fig. 7 is a similar view with the parts in a different position.

Fig. 8 is an end elevation of the inner end of the connecting link.

Referring in detail to the several figures of the drawing:

1 indicates the side members of a rectangular door frame which may be provided with a window 2 and also with suitable inner and outer walls 3 and 4 respectively forming the

walls of a window well into which the window 2 is slideable. Fastened within the window well in any manner is a supporting plate 5 provided with a flange 6 turned at right angles thereto and constituting a portion of one side edge of the frame. Fastened to the plate 5 as by pins 7 is a supplemental plate 8. Mounted on plate 5 is an angle piece 9 through the flange of which extends the shank 10 of a latchbolt, the head of which is indicated at 11 and which normally extends through a suitable opening in the flange 6 and into a keeper (not shown) when it is desired to retain the door in closed position. For normally holding the latchbolt in projected position a spring 11' is provided which is fastened to angle pieces 9 and encircles the shank of the bolt.

Mounted on plate 5 is a slideable plate or latch-bolt member 12 provided with slots 13 through which the headed pins 14 extend, said headed pins being secured to said plate 5. The slideable plate 12 is also provided with a flange 15 through which the shank 10 of the latchbolt extends and to which flange said shank is secured in any manner. The slideable plate 12 is also provided with a flange 16 adapted to be engaged by a roll-back 17 which is actuated by a handle 18 on the outer side of the door, the shaft of said handle extending through the righthand side member 1 and being connected with said roll-back 17 as ordinarily. When the handle 18 is rotated the roll-back 17 engages the flange 16 tending to move the slideable plate 12 rearwardly against the action of the spring 11' and consequently to retract the latchbolt 11 in an obvious manner.

19 indicates a link which is pivoted as at 20 to the slideable plate 12, the other end of said link being slotted as at 21 and receiving a headed pin 22 which is secured to a rotatable plate 23. The extreme inner end of said link 19 is provided with a projection 24 the other portions of said end of said link having a cam surface as indicated at 25. The said rotatable plate 23 is provided with a hollow bearing 26 mounted on and extending through the inner wall 3. 27 indicates the hub of an inside operating handle 28 which receives the bearing 100

26 and which is detachably secured thereto by a set-screw 29. Extending through the bearing 26 is a headed latching pin 30 the shank of which is provided approximately intermediate its ends with grooves 31 having beveled 5 walls all as more clearly indicated in Figs. 4 and 5. A portion of the hub 27 is recessed as at 32, said recess containing a detent 33 having a beveled end, as shown, adapted to engage within the grooves 31. The end of said detent is normally held in engagement with either of said grooves by the action of a spring 34 located within said recess 32.

When the latching pin 30 is pulled outwardly as shown in Fig. 5, the latchbolt 11 may be retracted by rotation of the outside handle 18 which slides the slidable plate 12 rearwardly carrying the link 19 with it, the pin 22 then sliding in the slot 21. When the 15 latchpin 30 is pressed inwardly in the position shown in Fig. 4 it is impossible, however, to retract the latchbolt by rotation of the outside operating handle as the projection 24 of the link 19 will abut against the end of the 20 shank of the latching pin 30 to hold the slid- 25 able plate 12 against rearward movement. As is obvious, the latching pin 30 may be pressed into latching position or pulled outwardly therefrom manually at will and during such 30 movement the end of the detent 33 is forced, against the action of the spring 34, from engagement with one of the grooves 31 and then into engagement with the other groove by the 35 action of said spring.

35 The latchbolt may be retracted by the inside operating handle 28 irrespective of the position of the locking pin 30. When the locking pin 30 is in retracted position and the handle 28 is rotated, the rotatable plate 23 is 40 also rotated, as is manifest, causing a rotation of the link 19 on the pivot 20 due to the pin and slot connection between said link and rotat- 45 ing plate. This pulls the movable plate 12 rearwardly drawing the latchbolt with it. Should the latching pin 30 be pressed forwardly into latching position the latchbolt 50 may be retracted by rotation of the handle 28 without the necessity of first pulling the latching pin outwardly manually. In this 55 case the end of the shank of the latching pin, upon rotation of the rotatable plate 23, is brought into engagement with the cam end 25 of the link 19 so that the latching pin, as shown in Figs. 5 and 7, is pressed into re- tracted position by said cam end.

The particular location of the inside operating handle is one of convenience also as it is unnecessary for the operator sitting in the conventional seat of an automobile to lean 60 forward in order to actuate said operating handle. It will also be noted that the inside operating handle 28 may be rotated in either direction for retracting the latchbolt.

What we claim as our invention is:

65 1. In a latch, a latchbolt, a rotatable plate,

a link pivoted to said latchbolt and to said plate and provided with a cam, a handle connected to said plate and a latching pin extending through said plate and adapted to be engaged by the cam of said link.

2. In a latch, a latchbolt, a slidable plate 70 connected to said latchbolt, a rotatable member, a pin on said rotatable member, a link pivoted to said slidable plate and having a slot receiving said pin and a handle for rotating said rotatable member to retract said latchbolt.

3. In a latch, a latchbolt member, a handle 80 for retracting said latchbolt member, a connection pivoted to said handle and said latch- bolt member and a latching pin for holding said latchbolt member against movement and adapted to be engaged by said connection.

4. In a latch, a latchbolt, a combined 85 handle and spindle for retracting the same, a connection between said handle and said latchbolt, a latching pin carried by said spindle and movable relatively thereto into locked or unlocked position and spring- 90 pressed means for holding said latching pin in retired or latching position.

5. In a latch for doors, a latchbolt, means 95 for retracting said latchbolt from the outside of the door, means remote from said latchbolt for retracting the same from the inside of the door and means carried by said remote means for latching said outside retracting means.

6. In a latch for doors, a latchbolt, means 100 for operating the same comprising a link connected to said latchbolt, a handle for actuating said link and a stop movable to position to prevent actuation of said link in a direction to retract said latchbolt by said handle, and means controlled by the rotation 105 of said handle for moving said stop to inoperative position.

7. In a latch for doors, a latchbolt, a plu- 110 rality of retracting means therefor having their axes parallel to each other but remote from each other and means co-axial with one of said retracting means for latching another one of said retracting means against movement.

8. In a latch, a latchbolt, a handle formed 115 with a supporting spindle and constructed for actuating said latchbolt, additional means for actuating said latchbolt, locking means for preventing movement of said bolt by said additional means, said locking means comprising a pin carried by said handle and movable relatively thereto to or from locking position, and means for automatically mov- 120 ing said pin into unlocked position upon movement of said handle.

9. In a latch for doors, a latchbolt, a handle, 125 a link connecting said latchbolt and handle, a stop movable to latching position to pre- vent movement of said link in a direction to retract said latchbolt, and means automati- 130

cally releasing said stop from its latching position upon movement of said handle.

Signed at New York, in the county of New York and State of New York this 11th day of November, A. D. 1925.
